RUDOLPH RUZICKA, OF NEW YORK, N. Y., ASSIGNOR TO THE J. B. WILLIAMS COMPANY, OF GLASTONBURY, CONNECTICUT, A CORPORATION OF CONNECTICUT.

DESIGN FOR A RECEPTACLE FOR TOILET COMPOUNDS.

No. 40,053.

Specification for Design.

Patented June 15, 1909.

Application filed February 18, 1909. Serial No. 478,745. Term of patent 14 years.

To all whom it may concern:

Be it known that I, RUDOLPH RUZICKA, a citizen of the United States, residing at New York, in the county of New York and State of New York, have invented a new, original, and ornamental Design for a Receptacle for Toilet Compounds, of which the following is a specification, reference being had to the accompanying drawing, forming part thereof.

Figure 1 is a front elevation of the receptacle. Fig. 2 is a side elevation.

The design consists of the surface orna-

mentation which includes sprays or stems extending lengthwise of the receptacle and bearing representations of the blossom known as a pink.

I claim—

The ornamental design for a receptacle for toilet compounds, as shown and described.

RUDOLPH RUZICKA.
